UNITED STATES PATENT OFFICE.

THOMAS H. CARROLL, OF PHILADELPHIA, PENNSYLVANIA, ASSIGNOR TO
THE CARROLL CHAINLESS CYCLE COMPANY, OF NEW JERSEY.

DESIGN FOR A BICYCLE-FRAME.

SPECIFICATION forming part of Design No. 26,954, dated April 20, 1897.

Application filed March 10, 1897. Serial No. 626,888. Term of patent 14 years.

To all whom it may concern:

Be it known that I, THOMAS H. CARROLL, of the city and county of Philadelphia, State of Pennsylvania, have invented a Design for Bicycle-Frames, of which the following is a specification.

My design is illustrated in the accompanying drawing, which shows a perspective view of a bicycle-frame embodying my design.

A is the usual center stay of the frame.

B is the crank-bracket.

C C are the back stays.

E E are the back forks, of which the back fork E on one side is composed of two parts F G, the part F extending from the back-fork end D and the part G from the crank-bracket B, the part G being nearer the central plane of the frame than the part F.

I is a brace-piece extending from the center stay A to the point of division of the back fork E into the parts F and G.

I have shown the design embodied in an ordinary diamond frame, but the particular character of the main portions of the frame is not material to my design, the essential ²⁵ feature of which is the divided back fork E, with the part I extending from the point of division of the parts F and G to the center stay A.

Having now described my invention, what ³⁰ I claim as new, and desire to secure by Letters Patent, is as follows:

The design for a bicycle-frame substantially as herein shown and described.

In testimony of which invention I hereunto ³⁵ set my hand.

THOS. H. CARROLL.
